BRUSH COMB WITH CURLER

Siegfried Behr, Flushing, N. Y., assignor to Ben Hur Products, Inc., New York, N. Y., a corporation of New York

Application May 15, 1939, Serial No. 273,699

5 Claims. (Cl. 132—19)

This invention relates to devices for combing, brushing and curling the hair and more particularly to that type which are to be carried in a lady's hand bag and ready for instant use.

5 It is an object of the invention to provide a device of the above kind which combines a pocket comb, a hair brush and a hair curler in such form that the three implements may be carried in a hand bag and used simultaneously, at least 10 some of them, and all of them successively, if desired.

It is another object of this invention to provide a device of this kind which is small and light enough for the stated purpose, which can 15 easily be handled and is always ready for instant use for any one, two or three functions to be performed therewith as desired.

With these and other objects in view the invention consists in the novel combination and arrangement of parts to be hereinafter fully described, claimed and illustrated in the accompanying drawing in which—

Fig. 1 is a top plan view of my new comb and brush curler showing the device arranged for brushing and combing the hair successively.

25 Fig. 2 is a front view of Fig. 1.

Fig. 3 is a front view similar to Fig. 2 showing the curler opened and the brush closed.

Fig. 4 is a top plan view of the device when 30 closed to be carried in a hand bag.

Fig. 5 is a front view of Fig. 4 showing the parts in position for combing and brushing the hair simultaneously.

Fig. 6 is a section on an enlarged scale on the line 6—6 of Fig. 5.

35 Fig. 7 is an exploded sectional view, on an enlarged scale, on the same plane as Fig. 6.

Fig. 8 is a detail view on an enlarged scale on the plane 8—8 of Fig. 7.

40 Fig. 9 is a detail section on the line 9—9 of Fig. 8.

Referring to the drawing, 10 is a comb, preferably of moldable plastic material such as acetate, plastic or the like. It consists of a back portion 10a which has a horizontally inclined top line and a lower horizontal longitudinal bottom line so that the back portion 10a is wider at its right end than at its left end, but its thickness is the same throughout. From the lower limit line, a plurality of teeth 11 which are integral with the back 10a extend downwardly, parallel to each other and all the teeth are of equal length so that their bottom line is parallel to the top horizontal line. As shown in Fig. 2 the back 10a of the comb extends a distance

tapering towards the right beyond the end tooth 11a of the comb as shown in Figs. 1, 2, 3 and 5. Against the front face of comb 10 leans a bar 12 which is provided on its lower face with bristles 12a to form a brush having a plurality of 5 rows of bristles, which bar is pivoted to the comb by means of a pivot pin or eyelet 13 in the extension 10a. To the rear side of comb 10 is pivoted by the same pivot 13 a curler bar 14. The brush bar 12 and curler bar 14 are each provided 10 with a cylindrical boss 12b and 14a respectively which surround the pivot 13 and are both lodged in a circular aperture of extension of 10a so that the eyelet 13 serves to hold the three parts together while the bosses 12b and 14a form 15 a journal within the bearing formed by the comb part 10a.

The extension 10a of the comb is also provided on its front and rear faces, each, with two pin-head projections 15 on the center line of 20 the extension which cooperate with small circular recesses 15a in the brush bar 12 and curler bar 14 to stop the swinging brush and curler bar in fully open and fully closed positions.

This device permits a lady to carry in her 25 hand bag the three most necessary implements for dressing her hair united in convenient form for instantaneous use and for simultaneous use of the comb and brush. Aside from the convenience of the device, it is very simply constructed and may be manufactured and sold to the public for a very reasonable price.

Changes in details of construction may be made without departing from the invention and I therefore desire to be limited only by the state 35 of the prior art and the appended claims.

I claim:

1. A comb having adjacent one end pivotally attached thereto a bar extending longitudinally of said comb and bristles on said bar forming a 40 brush parallel to the teeth of said comb and on the opposite side of said comb being pivotally held on a common pivot a curler bar extending parallel to said brush, said brush and curler bar being mounted to be independently 45 movable from each other and each adapted to be rotated into a position to extend longitudinally from the pivot end of said comb.

2. A comb having at one end pivotally attached thereto a bar extending longitudinally of said comb and bristles on said bar forming a brush 50 parallel to the teeth of said comb and on the opposite side of said comb being pivotally held on the same pivot a curler bar extending parallel to said brush, said brush and curler bar be- 55

- ing mounted to be independently movable from each other, and means on said brush and said curler bar to arrest said movable members in certain predetermined positions.
5. 3. A comb having teeth thereon, an extension at one end of said comb, a circular aperture in said extension, a pair of bars, one on each side of said comb extending longitudinally thereof, a cylindrical boss on each bar held within said aperture, a pivot pin passing through said two bars and bosses for joining said bars to opposite sides of said comb.
10. 4. In combination, a comb member, a bar hinged to one end of said comb and forming an extension thereof, a second bar hinged to the same end of said comb and forming an extension thereof, said latter bar having bristles thereon to form a brush, said bar members being adapted to be collapsed over said comb and 15 means on said comb and bar members for hold-
- ing said bar members in either extended or collapsed position, including pairs of projections on the comb member and coacting recesses on the bar members, said projections and recesses being positioned on either side of the hinge point and in alignment therewith.
10. 5. A comb having a back portion with teeth thereon, a pair of bars pivotally attached to one end of said back portion, one on each side thereof and normally parallel to the sides of said comb and being adapted to form an extension of the body portion, bristles on one of said bars parallel to the teeth to form a brush, the other bar being adapted to form a handle and being adapted to serve as a hair curler and means on said back portion to hold either one or both of said bars in either normal or extended position.
